(57) **CLAIM**

I claim the ornamental design for a shoring post, as shown.

DESCRIPTION

FIG. 1 is a perspective view of the shoring post of the present invention.

FIG. 2 is a side view of the shoring post of the present invention, the opposite side view being identical.

FIG. 3 is a cross sectional view of the shoring post of the present invention, taken along the line A—A shown in FIG. 2; and,

FIG. 4 is a top view of the shoring post of the present invention, the bottom view being identical.
